UNITED STATES PATENT OFFICE.

ROBERT W. NILSSON, OF TOLEDO, OHIO, ASSIGNOR TO THE MATHER SPRING COMPANY, OF TOLEDO, OHIO, A CORPORATION OF OHIO.

DESIGN FOR A BUMPER.

Application filed September 12, 1927. Serial No. 23,393. Term of patent 7 years.

To all whom it may concern:

Be it known that I, ROBERT W. NILSSON, a citizen of the United States, residing at the city of Toledo, in the county of Lucas and the State of Ohio, have invented a new, original, and ornamental Design for Bumpers, of which the following is a specification, reference being had to the accompanying drawing, forming a part thereof.

Fig. 1 is a front view of a bumper showing my design. Fig. 2 is a top view and Fig. 3 is an end view of the bumper shown in Fig. 1. Fig. 4 is an enlarged perspective view of the clamping plate shown in Fig. 1.

I claim:

The ornamental design for a bumper, as shown.

ROBERT W. NILSSON.
